STAND FOR DISPLAYING AND MERCHANDISING BANANAS

James Edward Doerr, Portsmouth, Ohio, assignor to Doerr and Associates, Inc., Portsmouth, Ohio, a corporation of Ohio

Filed Jan. 27, 1961, Ser. No. 63,728

Term of patent 14 years

(Cl. D80—9)

FIGURE 1 is a perspective view of a stand for displaying and merchandising bananas embodying my new design, and

I claim:

The ornamental design for a stand for displaying and merchandising bananas, substantially as shown.
